CLAIM

The ornamental design for toy robot convertible into an airplane, as shown and described.

DESCRIPTION

FIG. 1 is a front elevation view of a toy robot convertible into an airplane showing my new design;

FIG. 2 is a rear elevation view of the toy robot;

FIG. 3 is a right side elevation view of the toy robot, a left side elevation view being omitted which is symmetrical thereto;

FIG. 4 is a top plan view of the toy robot;

FIG. 5 is a bottom plan view of the toy robot; and

FIG. 6 is a modified form of the toy robot when converted to an airplane;

FIG. 7 is a top plan view of FIG. 6.

FIG. 2

FIG. 1

FIG. 4

FIG. 3

FIG. 5

FIG. 6

FIG. 7
